ELECTRIC CLOCK

Joseph Berti, Brooklyn, N. Y., assignor to Phinney-Walker Co. Inc., New York, N. Y., a corporation of New York

Application September 5, 1934, Serial No. 742,753

7 Claims. (Cl. 185—40)

This invention relates to electric clocks and the like.

The objects of the invention are to provide simple and inexpensive clock mechanism, which will be accurate and reliable, which will consist of but few and simple parts and in which the electrical mechanism will take up but small space, will be positive in its action and will be capable of storing energy for driving the clock train or other apparatus for an extended period of time.

The foregoing and other desirable objects are attained by the novel features of construction, combinations and relations of parts set forth in the following specification, illustrated in the accompanying drawings and broadly covered in the claims.

The drawings illustrate certain practical embodiments of the invention, but it will be appreciated as the invention is understood that the structure may be modified and changed in various ways, all within the true intent and broad scope of the invention.

Figure 1 is an embodiment of the invention as applied to the back movement plate of a clock, with the top plate broken away to disclose the gearing and with the winding mechanism in an intermediate position.

Figure 2 is a broken detail illustrating the parts at the instant of closing the switch to energize the solenoid.

Figure 3 is a similar view showing the parts as they appear after the solenoid has acted and the energizing circuit has been interrupted.

Figure 4 is a plan view of the parts appearing in Figure 1.

Figure 5 is an enlarged broken sectional detail of the solenoid and its contact making core.

Figure 6 is a broken sectional detail of the ratchet wheel and the mainspring lever.

Figure 7 is a broken detail illustrating a modification.

In the general views, Figures 1, 2 and 3, one of the main plates of the clock is indicated at 7, carrying the escapement end of the clock train at 8.

The power for driving the entire clock train in the present invention consists of a simple tension spring 9, connected to a lever 10, having a drive pawl 11 engaging ratchet 12 on an arbor 13, this arbor carrying the center wheel 14, engaging the reduction pinion 15, which through the intermediate wheel 16 drives the pinion 17 of the escapement train.

The mainspring lever 10 has a slotted engage-

ment at 18 with a pin 19 projecting from the core 20 of the solenoid magnet 21.

A special feature of the connecting pin 19 is that it is insulated from the core, as by being set in an insulating bushing 22. There is thus provided an electrically insulated mechanical connection between the solenoid core and the mainspring lever.

The core itself is electrically insulated from the movement plate 1 and parts mounted thereon, as by a construction such as illustrated in Figure 5, where the metallic center tube 23 in which the core slides is insulated from surrounding parts by the turns of the insulated coil 24 and the insulating end heads 25. The clamp 26 which secures the coil on the movement plate engages about the insulated winding or about an insulating cover over said winding. Thus, the solenoid is supported in insulated relation on the mounting plate and both the tube and the sleeve in which it is guided, remain insulated from the mounting plate.

One end of the solenoid winding is brought out to an insulated terminal, indicated at 27 in Figures 1 and 5, and the latter view shows how the opposite end of the winding is electrically connected with the insulated core sleeve at 28, so as to bring the core into the magnet circuit. To assure good sliding contact between the core and guide sleeve, there is provided in the illustration, a small spring pressed brush 29 in the core, lightly contacting the surrounding wall of the guide. The reaction of this spring tends also to hold the side of the core opposite the protruding brush in light sliding contact with the wall of the guide, doubly assuring good electrical sliding contact between core and guide.

To close circuit through the sliding core, there is provided in the present disclosure, a swinging lever 30, pivoted at 31 on the outer mounting plate 32 and swung in opposite directions by a spring 33, to carry one arm 34 of the forked end of the same into engagement with insulated pin 19, or the opposite arm 35 into engagement with contact pin 36. The latter is not insulated from the core, and consequently, when engaged by the arm 35, closes circuit through the movement plate on which the switch lever is mounted, completing electrical connections for the solenoid, substantially as indicated in Figure 2.

When circuit is closed as described, the solenoid immediately draws down the core, the pin 36 acting against arm 35, maintaining this circuit momentarily until a point is reached where

the spring 33, passing over the dead center position represented by the pivot center 31, will snap the switch lever downward into the position indicated in Figure 3, which movement is limited by the upper fork 34 engaging insulating pin 19.

In the outward movement of the core, under pull of the main spring 9, the insulated pin 19, by engagement with the upper fork 34, forces the switch lever upwardly until the spring 33, passing over the dead center represented by pivot 31, snaps the switch lever upwardly, back into the circuit closed position indicated in Figure 2. The circuit is thus both closed and interrupted with a snap action, assuring quick break and firm positive make.

The moment of circuit closing and energization of the magnet is determinable in the present disclosure by adjusting the anchorage point 20 of the switch throwing spring, by shifting the spring anchorage bracket 37 beneath the securing screw 38 and by shifting fork 34 in its secured relation beneath the screw 39. Either one or both adjustments may be used, as found desirable, and in some instances, with all factors properly worked out, one or both these adjustments may be eliminated.

The long stroke afforded by the solenoid provides a longer running time than can be attained by ordinary short stroke electromagnets. This long stroke also is desirable to effect the snap toggle action of the switch lever. In the short instant of time in which the solenoid is acting, the pawl 40 holds the ratchet 12.

A practical and at present preferred mounting of the mainspring lever is indicated in Figure 6, where this lever is shown as pivoted on the extended bushing 41 of the ratchet wheel 12, between a fixed abutment collar 42 and an anti-friction washer 43, loose at the face of the ratchet. The insulated pin 19 is shown in Figure 4, as extended in opposite directions to the mainspring lever 10 at one side and the forked switch lever 30 at the opposite side, which balances to some extent, the forces acting on the core, enabling it to slide smoothly in the guide sleeve. By placing the core in the magnet circuit, all wiring is avoided and by making the pin 36 serve as the insulated switch contact and the spring toggle lever as the grounded switch contact, the clock can be connected in circuit in an automobile, for instance, by simply bringing a wire on the live or ungrounded side of the battery to the one magnet terminal 27.

The mechanism consists in all of but few simple parts easily assembled and occupying but small space. A solenoid of relatively small size provides ample power for tensioning the spring sufficiently to run the gearing a considerable period of time. The movement of the switch toggle is made positive and direct by action of the abutment pins on the armature of the magnet.

The insulating of the solenoid core from other parts may be accomplished in various ways. Thus, the pin 19 might be set in the metal of the core and sleeves of insulating material be slipped over the ends of the pin protruding from opposite sides of the core. Instead of two pins, one pin only might be provided and the adjustable fork 34 be a piece of insulating material so as to carry no current when in contact with the pin. In place of the forked switch lever, a more or less straight lever might be employed, disposed to oscillate between the two pins or abut-

ments on the solenoid core. Other changes may suggest themselves truly within the scope of the invention.

In the form of the invention shown in Figure 7, a straight or non-forked switch lever is indicated at 35a having a single contact arm designed to be snapped into engagement with the contact pin 36, said lever being carried along with the core by a yoke extension 44 of the insulated pin 19, until the dead center position 10 of the spring toggle is passed in the upward or outer movement of the core. This single arm construction permits a longer stroke of the solenoid and hence accomplishes a longer running time of the movement.

The member 44 which travels along with the core and mainspring lever 10 may in fact be carried by the latter, positioned so as to effect the snap-over of the switch lever at the proper instant in the out movement of the core and lever. A back stop for the mainspring lever may be provided, such as the abutment pin indicated at 45. This pin comes into service when the magnet is disconnected from or the source of electricity is interrupted for any reason, permitting the movement to entirely run down, forming at such time a back stop for the lever and preventing the mainspring from drawing the core out of the solenoid.

It will be seen in Fig. 1 that as the main spring 9 draws the lever 10, upwardly in driving the movement train, the core 20 connected with that lever will be drawn upwardly out of the solenoid winding 21, and that in this outward movement the insulated pin 22, by engagement with the upper fork 34, of the spring toggle lever 30, will rock that lever until spring 33 passes over the dead center 31, whereupon the latter spring will snap this lever upwardly as in Fig. 2, to bring the lower fork 35, of said lever into engagement with the contact pin 36. When this occurs, an energizing circuit for the solenoid is established beginning with the insulated terminal 27, which is usually connected with the ungrounded side of the battery, through the coil and from the inner end of the coil at 28, Fig. 5, to the metallic solenoid sleeve 23, the spring connection 29 to the sliding core 20, the contact pin 36 on that core, to the fork 35 of switch lever 30. This lever is pivoted on the movement plate and the movement being grounded as customary, circuit is completed to the grounded side of the battery. The coil when thus energized draws in the core 20 and in so doing, the switch lever 30 is carried along by pin 36, acting against fork 35 until a point is reached where the toggle spring 33, again passes the dead center 31 and snaps the switch lever downward as in Fig. 3, carrying the lower fork 35, out of current carrying contact with the pin 36, and bringing the upper fork 34, back again into engagement with the insulated pin 22. The circuit making and breaking operations and the spring tensioning action of the solenoid are practically instantaneous. The operation then continues as first described, with the core moving outward under pull of the main spring, successively through the stages indicated in Figs. 3 and 1, until the switch lever is again snapped over to close circuit as in Fig. 2. The action of the form of the device illustrated in Fig. 7, is the same in substance as that described, it being apparent that the switch lever will be carried along in the outward movement of the core until the spring 33, passes over dead center and causes said lever to close circuit by contact of the por-

tion 35a with pin 36, on the core. In the inward movement of the core, the switch lever 30, is snapped away from this contact pin into engagement with the insulated core-carried element 44, by passage of spring 33, below the dead center represented by pivot 31.

What is claimed is:

1. Electric clock or similar mechanism, comprising in combination, a spring tensioned lever, a solenoid, a core actuated by said solenoid, an insulating connection between said core and said spring tensioned lever, means for connecting said core in circuit with the solenoid, a contact element on said core and a spring toggle switch lever having a part in cooperative relation to said contact element on the solenoid core.

2. An electric clock or similar apparatus, comprising in combination, a solenoid having an insulated center tube of conducting material and having its winding electrically connected at one end with said center tube, a core slidingly guided in said tube, a lever connected with said core, a spring acting on said lever, a switch lever, a contact on the core for cooperation with said switch lever and a spring for snapping said switch lever into and out of cooperation with said contact at different points in the travel of said core.

3. An electric clock or similar apparatus, comprising in combination, a solenoid having an insulated center tube of conducting material and having its winding electrically connected at one end with said center tube, a core slidingly guided in said tube, a lever connected with said core, a spring acting on said lever, a switch lever, a contact on the core for cooperation with said switch lever, a spring for snapping said switch lever into and out of cooperation with said contact at different points in the travel of said core and a spring brush providing continuous electrical contact between said solenoid tube and the core guided therein.

4. An electric clock or similar mechanism, comprising in combination, a solenoid, a core operated thereby and in the electrical circuit of said solenoid, an insulated and an uninsulated pin on said core, a lever in connection with said insulated pin and a spring actuated oscillating switch lever

cooperable at different times with said insulated and uninsulated pins on the core.

5. Electromagnetic spring winding means, comprising in combination a spring actuated lever, a solenoid provided with a metallic center tube and having one end of the solenoid winding electrically connected with said center tube, a core slidingly guided in and electrically connected with said center tube, insulated and uninsulated abutments on said core, said insulated abutment having mechanical engagement with said spring actuated lever, a toggle lever having fork arms cooperable with said insulated and uninsulated abutments and a spring connected to snap said toggle lever in opposite directions at predetermined points in the travel of said solenoid core in opposite directions.

6. An electric clock or like, comprising in combination with a driving spring, a member shifted thereby in one direction, a magnet having an armature connected with said member for shifting the same in the opposite direction, a magnet contact movable with said armature and shiftable member, a switch lever mounted for engagement with said contact and means traveling with said armature and shiftable member for carrying said switch lever into engagement with said magnet contact, and a pivot pin connecting said armature and shiftable member, said pivot pin having an extension forming the means for shifting the switch lever into engagement with the magnet contact.

7. Electromagnetic spring winding means, comprising in combination, a solenoid having an insulated center tube of conducting material and having its winding electrically connected at one end with said conducting center tube, a terminal for the opposite end of the solenoid winding, a solenoid core operating in said tube, spring means forming resilient electrical connection between said conducting center tube and solenoid core, a contact on the end of the solenoid core, a spring lever engageable by said core carried contact and means for establishing electric circuit connections with said spring lever and said winding aforesaid.

JOSEPH BERTI.
